UNITED STATES PATENT OFFICE.

JAMES CLARENCE ROGERS, OF GRAYSON, GEORGIA.

CARBURETER.

1,111,763.

Specification of Letters Patent. Patented Sept. 29, 1914.

Application filed October 1, 1913. Serial No. 792,845.

To all whom it may concern:

Be it known that I, JAMES C. ROGERS, a citizen of the United States, residing at Grayson, in the county of Gwinnett and State of Georgia, have invented a new and useful Carbureter, of which the following is a specification.

This invention relates to improvements in carbureters for explosive engines.

10 An object of the present invention is to provide a carbureter particularly adapted to vaporize the heavier and less volatile oils, such as kerosene.

15 A further object of the invention is to provide a carbureter with automatic controlling means whereby the amount of fuel delivered to the mixing chamber will be proportional to the air entering therein, whereby a proper mixture of the two ingredients 20 for the formation of a combustible gas will at all times be had.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 30 within the scope of what is claimed without departing from the spirit of the invention.

In the drawings accompanying this specification and forming a part thereof, the preferable form of my invention is illustrated, in 35 which—

Figure 1 is a vertical sectional view of a carbureter embodying the features of my invention. Fig. 2 is a cross sectional view thereof taken on the line 2—2.

40 Referring to the drawings, in which similar reference numerals designate corresponding parts throughout the several views, an air inlet pipe 3 communicates with the mixing chamber 4 and from which latter extends the outlet and delivery pipe 5. A liquid fuel chamber 6 is supported by a bracket 7 which latter extends between the mixing chamber and the fuel outlet pipe 5.

The air inlet pipe 3 is provided with a 50 butterfly valve 8, the movements of which are controlled by the arm 9, the latter being provided with a set screw 10 engaging an arc 11 for the holding of the butterfly valve in any adjusted position. A similar butterfly valve 12 is located in the outlet or delivery pipe 5 and is provided with a crank

arm 13, which latter has the aperture 14 extending through the outer extremity thereof and may be connected to the controlling levers so that this valve may also be held in adjusted positions.

The liquid fuel chamber 6 is provided with the fuel inlet pipe 15 with a suitable valve 16 controlling the same, the upper extremity of the valve stem being pivotally connected to a buoyant float 17 so that the liquid fuel will be maintained at a constant level in the fuel chamber. An outlet pipe 18 communicates with the lower portion of the fuel containing chamber 6 and terminates in the mixing chamber 4 into which it is adapted to supply the liquid fuel. A plunger valve 19 is adapted to control the supply of liquid fuel passing through the fuel supply pipe 18 into the mixing chamber 70 and is pivotally secured to the lever 20 so that a raising of the outer extremity of the lever 20 will result in the opening of the valve and allowing the passage of the liquid fuel into the upper portion of the mixing 75 chamber 4. The fuel containing chamber 6 is rigidly secured to the bracket 7 by set screws 21 or other equivalent means and which also hold the bracket to the mixing chamber.

80 Extending across the air inlet pipe 3 is a supporting bracket 22 which provides a bearing for a shaft 23 which extends longitudinally of the mixing chamber, extends through the base thereof as at 24 and terminates in a thrust bearing 25 which is supported by a sub-frame 26. The shaft 23 is provided with an outstanding blade 27 secured thereto, and which as will be apparent from a reference to Fig. 2, is in the nature 90 of broad flat surfaces, preferably formed of wire, the mesh of which is sufficiently fine so as to break the liquid fuel as it drops from the pipe 18 into an infinite number of fine particles of vapor-like consistency. A 95 propeller 28 is rigidly secured to the upper extremity of the shaft 23 and is positioned within the air inlet pipe 3 so as to be rotated by the air as it passes therethrough for the rotation of the wire blade 27.

100 The sub-frame 26 whereby the thrust bearing 25 is supported comprises the arm 29 secured to the outlet delivery pipe 5 as at 30 and also secured to the mixing chamber 4 as at 31. The sub-frame extends for some 110 little distance below the lower extremity of the mixing chamber and outlet pipe 5 and

between which extends the bracing arm 32. The sub-frame 26 may take the nature of a casing so as to exclude dust and foreign material therefrom which would prevent the proper workings of the various rotating and oscillating parts disposed therein. A ball governor 33 is rigidly secured to the lower extremity of the shaft 23 and is rotated therewith and is provided with the collar 34 which is provided with the central grooved portion 35, engaging which are the levers 36 and 37. The lever 36 is pivotally secured as at 38 to the desired wall of the sub-frame and extends therebeyond, terminating in a handle or manually engageable portion 39 whereby the governor and parts connected thereto may be raised to produce a result similar to the raising of the governor balls by an excessive rotation of the shaft 23.

The lever 37 which also engages the lowered portion 35 of the collar 34 is pivotally mounted upon the upstanding column 32 intermediate its ends so that a downward motion of the one extremity of the lever will result in the corresponding upward motion of the opposite end thereof. The free end of the lever 37 is pivotally connected to a link 40, the upper extremity of which is pivotally secured to the lever 20 of the valve 19. Thus as the governor balls are driven outwardly by centrifugal force during the excessive rotation of the shaft 23, the one extremity of the lever 37 will be drawn upwardly and the opposite end and to which the link 40 is pivotally secured will be drawn downwardly resulting in the plunger 19 being moved up toward its valve seat for a cutting off of the supply of fuel through the full supply 18.

From the foregoing it will be apparent that the fuel entering the mixing chamber is controlled by the position of the governor balls or may also be manually controlled by the lever 39.

Thus with the improved form of carbureter as herein described, the liquid fuel as it passes into the mixing chamber from the pipe 18 will encounter a rapidly rotating blade rotating about an axis parallel to the natural fall of the liquid so as to intercept the path thereof and the blade being formed of a wire of somewhat fine mesh will break the fuel into fine particles of spray like form and thus provide for the efficient and rapid evaporation or volatilization of the same. The rotation of the blade 27 is accomplished by the propeller 28 and is thus proportional to the amount of air passing through the pipe 3. Thus it will be apparent that the greater the amount of air passing through the pipes, the greater will be the speed at which the fan blade 27 is rotated so as to insure the proper division and breaking up of the fuel. Also it will be noted that the

amount of fuel entering the mixing chamber will be proportional to the speed of rotation of the shaft 23 which in turn is proportional to the quantity or volume of air passing through the inlet pipe 3 and which will be readily appreciated is a function of the speed of rotation of the engine. The shaft 23 and parts secured thereto and which rotate therewith, are preferably formed of light material so that the moments of inertia will be kept as low as consistent with the rigid construction and durability of the entire device and which renders the carbureter here described extremely sensitive to changes in the speed of rotation of the engine and allows for the same to quickly and properly take up the extra load which may be brought to bear upon the engine by increasing the fuel supply necessary therefor. The sensitiveness of the entire device is of extreme importance as it allows for a fine degree of adjustment to be had. Also attention is called to the fact that with the carbureter as herein described kerosene and other hydrocarbons which are not easily volatilized may be used due to the manner in which the blade 27 will break up the liquid into a spray of vapor-like form.

Having thus fully described my invention, what I claim is:

1. In a carbureter, the combination of a liquid fuel containing chamber with means disposed therein for maintaining the fuel at a constant level, a mixing chamber in communication with and adapted to receive liquid fuel from the said fuel containing chamber, air inlet and gaseous fuel outlet pipes communicating with the said mixing chamber at the upper and lower extremities thereof respectively, a shaft extending longitudinally of said mixing chamber, a foraminous blade carried thereby and arranged adjacent the fuel inlet of the mixing chamber, said foraminous blade intercepting the path of flow of liquid fuel through said mixing chamber to reduce the same to a spray, and a propeller carried by the said shaft disposed within the said air inlet pipe and rotated by the ingestion of air taken with respect to said mixing chamber.

2. In a carbureter, the combination of a mixing chamber, an air inlet and a gaseous fuel outlet pipe communicating therewith, a liquid fuel containing chamber, a liquid fuel outlet pipe communicating with said fuel containing chamber and the upper portion of said mixing chamber, a valve disposed within said pipe controlling the flow of liquid therethrough, a propeller disposed within said air inlet pipe actuated by the passage of air therethrough, a shaft supporting and actuated by said propeller, a foraminous blade carried by said shaft and rotated thereby, said foraminous blade rotating to intercept the path of flow of liquid

from said mixing chamber, fuel supply pipe, and means secured to said shaft and connected to the said valve controlling the position of said valve and positioning the same functional of the speed of rotation of said shaft.

In testimony that I claim the foregoing

as my own, I have hereto affixed my signature in the presence of two witnesses.

JAMES CLARENCE ROGERS.
